ALEXANDER E. KEITH, OF CHICAGO, ILLINOIS, ASSIGNOR, BY MESNE ASSIGNMENTS,
TO AUTOMATIC ELECTRIC COMPANY, A CORPORATION OF ILLINOIS.

INDIVIDUAL-SWITCH MECHANISM FOR AUTOMATIC TELEPHONE SYSTEMS.

1,304,324.

Specification of Letters Patent.

Patented May 20, 1919.

Application filed April 29, 1905, Serial No. 258,026. Renewed August 15, 1914. Serial No. 256,990.

To all whom it may concern:

Be it known that I, ALEXANDER E. KEITH, a citizen of the United States of America, and resident of Chicago, Cook county, Illinois, have invented a certain new and useful Improvement in Individual-Switch Mechanism for Automatic Telephone Systems, of which the following is a specification.

10 My invention relates to automatic telephone systems in general, but more particularly to automatic telephone systems of that general type in which automatic switches are employed in place of the well-known 15 manual switchboards, and especially to automatic telephone systems of that character in which the connections between subscribers' lines are brought about by the calling subscribers through the medium of switches 20 or switching machines which operate on the step-by-step principle—that is, switches or switching machines provided with circuit-closing means adapted for making any one of a number of possible connections, and in 25 which any particular or desired connection is brought about in a step-by-step manner and in response to one or more electrical impulses transmitted over the "line-circuit" from the calling subscriber's station. In 30 changes of this general character, the number of switches or switching machines necessarily employed by any calling subscriber in establishing the desired connection depends, of course, upon the size and capacity 35 of the exchange,—i. e., the number of subscribers having lines terminating at the exchange or central station. For example, the exchange may be of such size that the calling subscriber will necessarily employ a "first selector", a "second-selector" and a "connector" in making the desired connection, which 40 would be the case if the number of the called subscriber contained four digits; but as will hereinafter more fully appear, a less number 45 of switches will be employed by a calling subscriber if the number of the called subscriber contains but two digits. The so-called "first selectors" are the switches or switching machines which receive the current-impulse or impulses representing the 50 first digit of the called number, while the so-called "second-selectors" are the switches or switching machines which receive the current-impulse or impulses representing the 55 second digit of the called number. A "con-

necter", however, is the switch or switching machine which receives and responds to the electrical impulse or impulses representing the last two digits of the called number, and which makes the final connection directly 60 with the line of the called subscriber. In the system to which my invention more particularly relates, a "selector", whether it be first, second, third, fourth, etc., is preferably so constructed that it can be controlled 65 directly by the calling subscriber for picking out a particular group of trunk-lines; but after being thus operated by the calling subscriber, it then ceases to be under the control of the calling subscriber, and proceeds 70 automatically to pick out and establish connection with the first idle trunk-line which it finds or encounters during its automatic search, so to speak, through the said group of trunk-lines. In this way, one or more 75 "selectors" can be employed by a calling subscriber in establishing connection with a "connector", and the latter can then be employed for picking out and making connection with the line of the called subscriber; 80 but the "connector" is, during its operation, always under the control of the calling subscriber, and does not only respond to the calling subscriber's acts for the purpose of 85 picking out the particular group of subscriber's lines in which the called subscriber's line is included, but also then performs another operation which is strictly in accordance with the switching operation at the 90 calling subscriber's station, and for the purpose of picking out the particular or exact subscriber's line with which the calling subscriber desires to establish connection. And in each case, it will be understood that the 95 step-by-step operation of a "selector", or of a "connector", is brought about or initiated by the transmission of one or more electrical impulses in the "line-circuit", the well-known arrangement for this purpose consisting of subscribers' switching devices by 100 which a make-and-break action may be produced at will in a grounded "line-circuit" including the "line-relay" of the particular switch or switching machine which the calling subscriber is operating.

In a system of this kind, and prior to the invention described in my application Serial No. 229,373, filed October 21, 1904, it had always been customary, where it was desirable or necessary to trunk to different trunk

105

110

dred-groups of connectors, according to the character of the called number, to provide a "first-selector" for each subscriber's line—that is, to provide a number of "first-selectors" corresponding in number to the total number of subscribers, and to then arrange the other "selectors," if any were employed, and also the "connectors," on a percentage basis—that is to say, in such manner that the total number of "second-selectors," for example, would be one-tenth of the total number of subscribers. In other words, it had been customary, where it was necessary or desirable to provide means for trunking to different groups of connectors, to provide each subscriber's line with a switching machine which received number-impulses from the sub-station to which it was allotted, and which was used by that particular subscriber and no others; and with such arrangement it is evident that an exchange will include a quantity of switching machines corresponding in number to the total number of subscribers, and each of which is required to perform a maximum of work; *i. e.*, to perform a switching operation corresponding to the first digit of the called number, and involving vertical and rotary motion of its switch-shaft, which motion may be as great as that of any other machine in the exchange. In my said prior application, however, I provide each subscriber's line with an "individual-switch" which is never called upon to respond to number-impulses, and which is subjected to a minimum of wear and tear, for this reason;—namely that it automatically picks out an idle trunk-line leading to a "first-selector," and does so in a very easy and comparatively simple manner, as it is never called upon to respond to more than a single impulse. In this way, a comparatively small amount, and practically minimum amount, of work is assigned to the switches which are individual to the different subscribers, and consequently the "selectors," as, for example, the "first-selectors," can be considerably less in number than the total number of subscribers; and with all the switches or switching machines, which are called upon to respond to number-impulses, thus arranged on a percentage basis, it is evident that the "individual-switches" may be characterized by the simplest and most economical construction and mode of operation; for in practice I find that efficient service can be given the subscribers by employing only ten trunk-lines to each "individual-switch"—that is to say, by making it necessary for each "individual-switch" to automatically search through only ten trunk-lines in order to find one which is idle and in condition for use by the calling subscriber. With the old arrangement, involving a "first-selector" for each subscriber's line, it is evident that in a large exchange each "first-

selector" would necessarily be adapted for making connection with substantially one hundred trunk-lines, thereby making it necessary for each "first-selector" to first pick out the desired group of ten trunk-lines, and to then perform another operation for the purpose of picking out from this group of ten trunk-lines one which is idle and in condition for use. As explained, however, and as set forth in my said prior application, these more complicated operations are now assigned exclusively to switches or switching machines which in number may be only ten per cent. of the total number of subscribers, while the switches or switching devices which are necessarily individual to the different subscribers' lines are each so simple in operation as to insure greater efficiency and economy with respect to the operation and maintenance of the system as a whole. 85

Generally stated, the object of my present invention is the provision of an improved and highly efficient "individual-switch" mechanism for use in automatic telephone systems of the foregoing general character, and to thereby reduce the cost of installation and maintenance of the system as a whole, inasmuch as each "individual-switch" may be of a comparatively simple and cheap construction, and characterized by such a simple mode of operation as to materially reduce the wear and tear upon its different operative parts. 90

A special object is to provide an improved construction and arrangement whereby all idle "individual-switches" will always be in position to connect with an idle trunk-line, thereby making it unnecessary for each "individual-switch", when employed by its allotted subscriber for establishing connection with a trunk-line leading to another switch, to do anything more than simply close the connection which is already in waiting for it, and to thus make the desired connection without resorting to any step-by-step movements, and without resorting to any searching operation, so to speak, the searching for an idle trunk-line having been done previous to the use of the "individual-switch" by the last calling subscriber, and while the switch was idle. 105 110 115

Another object is to provide an improved construction and arrangement of such character that the "individual-switch" may be operated by a single electrical impulse projected over the line by some act on the part of the calling subscriber, but which impulse is not a preliminary impulse as far as its being transmitted prior to and independently of the entire calling operation is concerned, although it is a preliminary impulse in the sense that it necessarily traverses the "line-circuit" for the purpose of making the preliminary connection with an idle trunk-line, and before the initial actuation of the "first- 120 125 130

selector" or other switch or switching machine picked out by the "individual-switch" and employed for receiving the impulse or impulses representing the first digit of the called number, and for performing the necessary switching operation corresponding to the first digit of the called number, the operation of the "individual-switch" being so rapid that the first number-impulse transmitted by the calling subscriber in actually calling the desired number will suffice for both purposes—that is, will perform the two functions of actuating the "individual-switch" and thus establishing connection with an idle trunk-line, and of then initially actuating the "first-selector" or other switching machine, and thereby making it possible to operate both the "individual-switch" and the "selector" and "connector" switches by means of the ordinary calling device at the subscriber's station.

A further object is to provide an improved construction and arrangement of such character as will obviate the necessity of providing any wipers or other traveling switch-contacts, and as will permit all of the different possible connections which the "individual-switch" is capable of making to be accomplished through the medium of a plurality of spring-switches each complete in itself and provided with all contacts necessary for making the connection for which it is employed, only the means for operating the different spring-switches, such, for example, as a key or plunger of insulating material, being common to all of said spring-switches, and consequently to all of the different trunk-lines leading from the "individual-switch," but there being no necessity, with this arrangement, of employing wiper-cords and wipers which travel from one position to another for the purpose of making a connection here or there, as the case may be.

Another object is to provide an improved construction and arrangement involving a mechanical bridge-cut-off adapted automatically to disconnect the "line-relay" of the "individual-switch" as soon as the latter is thrown into an operated position—that is, a position necessary for establishing any one of the different possible connections.

A further object is to provide an improved construction and arrangement whereby the idle trunk-selecting means will quickly and automatically return to its normal or initial position after it has successively put into use each of the trunk-lines allotted to the "individual-switch," and whereby said means will then be in condition to again search among the same set of trunk-line-terminals for an idle trunk-line, the search each time being first among those trunk-line-terminals which were first put in use and which would, therefore, be most likely to be disengaged and out of use.

Another object is the provision of improved means for clamping the magnet-coils in position and for readily adjusting the same.

A further object is to provide an improved construction and arrangement of such character that when the parts of an "individual-switch" are returned to their normal or idle positions, the key or plunger of such "individual-switch" will be thrown into line with the like plungers or keys of all other idle "individual-switches," and thus brought into position to engage an idle set of trunk-line bank-springs or trunk-terminal-springs as soon as the subscriber to whom the "individual-switch" is allotted sends in another call, the arrangement being such that when one or two or three of the "individual-switches" are in use, so that one or two or three or any other number of the trunk-lines are occupied, the plungers or keys of the other or idle "individual-switches" are all in line, and such that as fast as the trunk-lines are occupied or put into use, the idle plungers or keys are moved to a position opposite the next idle trunk-line, thus always making it possible for a calling subscriber to accomplish the desired preliminary connection with a trunk-line without moving his "individual-switch" from the position in which he finds it when he starts to make the call.

It is also an object to provide certain details and features of improvement, and certain features of construction, tending to increase the general efficiency of an automatic telephone system of this particular character.

To the foregoing and other useful ends my invention consists in the matters hereinafter set forth and claimed.

In the accompanying drawings, Figure 1 is a plan of two of my improved "individual-switches," showing a section of the shaft which is common to all of the "individual-switches" in the particular group to which those shown belong, and showing also the step-by-step mechanism which is common to all of said switches, and which is employed for rotating said shaft.

Fig. 2 is a section on line 2—2 in Fig. 1, showing the automatic step-by-step rotating mechanism in end elevation.

Fig. 3 is a detail view of the wiper and adjacent parts of the automatic step-by-step mechanism.

Fig. 4 is a detail perspective showing the contacts and the end of the arm for interrupting the current which energizes the magnet employed for producing the step-by-step rotation of the shaft.

Fig. 5 is a detail sectional view of the bank of contacts employed in the said step-by-step mechanism.

Fig. 6 is a section on line 6—6 in Fig. 1, showing one of the "individual-switches" in

side elevation, and in its normal position, the main shaft and certain other parts being shown in section.

Figs. 7, 8 and 9 are detail views of certain portions of the contact-banks of the "individual-switch".

Fig. 10 is a detail sectional view of one of the contact-banks of the "individual-switch", showing the plungers or keys in engagement with the flexible or movable circuit closing springs of the said banks.

Fig. 11 is a view similar to Fig. 10, but showing the said plungers or keys withdrawn and out of engagement with the switch-springs of the bank.

Fig. 12 is a diagrammatic view showing the operating circuits of the "individual-switch", and showing the circuits of the step-by-step mechanism for rotating the switch-shaft.

Fig. 13 is a diagrammatic view illustrating the method of multiplying together the bank-contacts of the "individual-switches", and of connecting the same to the bank-contacts of the step-by-step mechanism for rotating the shaft.

Fig. 14 is a diagrammatic view showing a calling subscriber's line connected with a called subscriber's line, and showing the connection established through the medium of an "individual-switch" and a "connector", it being assumed for convenience of illustration and description that the exchange is of such size that "selectors", either first, second, third, etc., are not necessary in making connection between any two subscribers' lines.

Fig. 15 is a diagrammatic view showing the circuits and operative parts of a well known and well understood form of "connector".

Referring to Figs. 1 to 5, inclusive, it will be seen that the switch-operating machine, or step-by-step mechanism for operating the switch-shaft 1, comprises a pair of "rotary-magnets" 2 and a "rotary-relay" 3, all of said electro-magnets being preferably supported upon an arm or bracket 4 secured to the rack-bar 5. This bar 5, together with the other rack-bar 6, constitutes the means for supporting the "individual-switches" and the switch-operating machine, it being understood that all of the "individual-switches" and their switch-operating machine can be removably mounted upon a suitable rack. The shaft 1 is preferably supported in a horizontal position by means of a bearing 7 at one end, and by means of a suitable bearing at its other end, it being observed that the "individual-switches" are distributed along the length of said shaft—that is, along the length of that portion of the shaft which is composed of the angle-iron or L-shaped piece 8. At its end, the said shaft is provided with a

clock-spring device 9, of any suitable or desired character, for yieldingly holding it in its normal position, and for automatically returning it to its normal position when released after traveling around to the limit of its step-by-step rotary motion. As illustrated, the said shaft is provided with a wiper or movable switch-arm 10 adapted to coöperate with the set of contacts arranged in a single row in the bank 11. It will be seen that this bank comprises ten contacts 12, arranged in a semi-circle about a horizontal axis coincident with the shaft 1, and that these contacts are arranged upon one side of a strip of insulation 13, while a continuous contact-plate 14 is positioned at the opposite side thereof. The ten contacts are provided with terminals 15, and the said contact-plate with a terminal 16. The wiper 10 is preferably bifurcated at its end, so that it may not only slide around upon the said contact-plate 14, but may also swing around and travel from one contact 12 to the next. These contacts are all insulated from each other, and from the said contact-plate, and are preferably clamped between two metal plates 17 and held together by means of screws 18. The means for communicating motion from the "rotary-magnets" 2 to the shaft 1 consist of an armature 19 pivoted at 20 and arranged just above the said magnets, together with a cam 21 on the said shaft, a ratchet-wheel 22 having pins 23 adapted to engage the said cam, and a spring pawl 24 mounted upon the said armature and adapted to engage the said ratchet-wheel. It will be seen that the "rotary-magnets" are secured to a bracket 25, which latter is in turn secured to the bracket-plate 4; and it will also be seen that the said armature is pivotally mounted on the upper end of the bracket 25. A retracting-spring 26, secured at one end to the said armature and engaging a screw 27 with its other end, constitutes the means for keeping the said armature normally away from the "rotary-magnets". As shown, the said armature is provided with a relatively short arm 28 adapted to be held normally in engagement with the bracket 25 by the tension of the spring 26. It will be seen that the screw or adjusting device 27, for regulating the tension of the spring 26 is screwed into the bracket 25. The pawl 24 is pivoted at 29 to the arm or end portion 30 carried by the said armature. A spring 31, connected at one end with the rear end of said pawl, and at its other end with the said arm or end portion, constitutes the means for yieldingly pressing the said pawl into engagement with the teeth of the ratchet-wheel 22. The said armature is limited in its movement away from the "rotary-magnet" by the engagement of the arm 28 with the bracket 25, and in its movement toward the said magnet.

by the engagement of the interrupter-arm 32, also carried by the armature, with the stationary stop 33, the latter being carried by the bracket-plate 4. This interrupter-arm 32 is provided with an end portion 34 adapted to open and close the switch-springs 35 and 36, the latter being normally in engagement with each other, and suitably secured to the bracket-plate 4 by means of 5 screws 37. These switch-springs 35 and 36 are arranged at either side of an intermediate or operating-spring 38, it being observed that both of said switch-springs have their outer ends bent laterally to provide end 10 portions located at opposite sides of the operating-spring 38. A piece of insulation 39, secured to the spring 36, prevents the latter from engaging or making electrical contact with the spring 38. The laterally-projecting end portion 34 of the interrupter-arm is adapted to engage the end portion of the spring 38, and when the armature is attracted this end portion 34 then bears upon the end portion of the spring 25 35, and then slips off from the same and engages the spring 38. This separates the springs 35 and 36, and when the armature is released the portion 34 then travels back between the spring 38 and the end portion 30 of the spring 35, thus insuring a complete separation of the springs 35 and 36 until the armature is fully retracted or restored to its normal position. The stroke of the armature is sufficient to move the ratchet-wheel one tooth each time it is attracted, it being observed that the arm or stop 33 is adapted to guide the pawl 24 into engagement with the ratchet-teeth. A locking-dog 40, mounted on the bracket 4 and controlled 35 by a spring 41, engages the ratchet-wheel 22 and prevents back rotation of the latter. It will be seen that the cam 21 has a curved or concave cam surface 42 adapted to be engaged by the pins 23 on the ratchet-wheel. 45 In Fig. 2, the mechanism is shown in its normal condition—that is, with the wiper 10 on the first contact of the bank 11, and the cam 21 in engagement with one of the pins 23. When the "rotary-magnets" are energized, the single step imparted to the ratchet mechanism will be communicated through the cam 21 to the arm or wiper 10, the movement being just sufficient to carry the wiper from the first to the second contact. In this way, each energizing impulse received by the "rotary-magnet" brings about a rotary step on the part of the ratchet mechanism, and consequently another step on the part of the switch-wiper 10. It will 55 be seen that the cam is so shaped that its end or point is disengaged from the pin as soon as the wiper 10 disengages the last contact in the bank, thus permitting the clock-spring device 9 to restore the shaft 60 1 and all parts operated thereby to their normal or starting point positions. As soon as the cam 21 is disengaged from one of the pins 23, it immediately falls into engagement with the next pin, and consequently the mechanism is always in readiness to convert an electrical impulse in the "rotary-magnets" into a single step on the part of the shaft-wiper 10. In other words, the ratchet mechanism always operates in one direction, the ratchet wheel always rotating in the same direction; but this constant motion in one direction on the part of the ratchet mechanism serves to alternately operate and release the wiper 10, thereby giving the latter a back and forth movement over the contacts. It will be seen, however, that the forward movement of the wiper 10 is of a positive nature, as it is brought about by the positive actuation of the ratchet mechanism, while the return or 70 back movement of the said wiper is automatic and brought about by a spring after its disengagement from the operating mechanism. In this way, the wiper 10 has a comparatively slow or step-by-step movement in a forward direction, but has a quick return movement. As shown, the relay 3 has an armature 43 which is pivotally mounted at 44 and provided with an arm 45. This arm is provided at its end with a piece of insulation 46 adapted to operate the normally-separated switch-springs 47. When the relay is energized, its armature closes these springs 47, as will hereinafter 75 80 85 90 95 100 more fully appear.

Referring more particularly to Figs. 1 and 6 to 11, inclusive, the construction of each "individual-switch" is preferably as follows: Each "individual-switch," as thus illustrated, comprises a "line-relay" 48 composed of two suitably connected electro-magnets arranged in a horizontal position one above the other. The cores 49 of the said relay-magnets are of sufficient length to extend through openings in the vertical flange 50 carried by the body-frame 51. At opposite sides of this vertical flange are arranged the bowed or sprung straps 52 and 53, the same being provided with end portions having openings adapted to receive the cores of the said relay-magnets. In other words, the said straps are arranged flatwise upon and at opposite sides of the said flange, and in such position that their openings register with the openings in the flange, so that the relay-magnet-cores project through the three superimposed thicknesses of metal. At the center of the three thicknesses of metal thus arranged flatwise together, a screw 54 is applied in such manner that it turns loosely in the said flange and the strap 53, but has its threaded end portion in threaded engagement with a threaded opening in the strap 52. Obviously, with this arrangement, a tightening of the said screw tends to produce 110 115 120 125 130

an endwise or lengthening movement on the part of the two straps, thereby causing the same to push and clamp the cores tightly against the outer sides of the openings in the 5 flange—that is, a tightening of the screw tends to produce a shearing action, thereby clamping the cores in place. It will be seen that the said screw can be loosened, thereby loosening the cores in their openings, and 10 thus permitting the relay-magnets to be easily and accurately adjusted. The so-called "release-magnet" 55, consisting of two electro-magnets, is secured to a flange 56 in a similar manner. In this case, the straps 15 57 and 58, together with the screw 59, constitute the means for clamping and holding the end portions 60 of the magnet-cores. This "release-magnet" is provided with an armature 61 which is pivoted at .62, so that 20 it may swing about a horizontal axis, and thus be operated by the lower end of the said "release-magnet." The said armature is provided with a relatively short arm 63 adapted to be engaged by a spring 64^a. Another spring 64, it will be seen, is coiled around the pin 65, and thence around the pivot or axis 66 provided for the plunger-arm 67. The end portion of said spring is then applied to this arm 67 in such manner 25 that it tends to depress the right-hand end portion of the said arm. In this way, the spring 64^a serves as the means for holding the armature 61 normally away from the lower end of the "release-magnet," and for 30 depressing the longer end portion of the plunger-arm 67 when the latter is released by the armature-latch or "release-link" 68. It will be seen that this latch or release-link 68 is provided at its upper end with a hook 35 69 adapted to slide upwardly upon the left-hand end of the arm 67, but so formed that it cannot be drawn downward without then engaging the said arm and drawing the latter into its normal position. At 40 the said latch or release-link is pivotally secured to the armature 61. It will also be seen that the said latch or release-link is provided at its lower end with an arm 71 adapted to be engaged by a spring 72 carried by the said 45 armature. In this way, the spring 72 permits the latch or release-link 68 to swing outwardly for the purpose of either disengaging the arm 67, or of rising into position to engage and draw the said arm into its normal 50 position. As shown, the said latch or release-link 68 serves as the armature for the "line-relay" 48—that is, when the said "line-relay" is energized it attracts this latch or release-link and thereby releases the 55 plunger-arm 67. The said plunger-arm is provided at its end with a pivoted plunger 73. The end portion of this plunger is provided with two pointed switch-plungers or 60 keys 74 and 75, the same being preferably of 65 hard rubber or other insulating material.

The upper end portion of the plunger 73 is adapted to fit the hollow or concave side of the angle-iron 8, which latter, it will be borne in mind, is a part of the switch-shaft 1. In conjunction with this plunger, the 70 "individual-switch" comprises a bank 76 of spring-contacts adapted to be operated by the pointed end portions of the said plunger. These contacts are, it will be seen, arranged in two rows, the contacts in one row being 75 "line-contacts," and those in the other row being contacts for closing circuit through the "rotary-relay" 3, and also through the "release-magnet" 55, as will hereinafter more fully appear. The two rows of contacts 80 may be substantially the same in character, each consisting of ten pairs of spring-contacts normally out of engagement with a pair of continuous contact-plates between which all of the pairs are arranged. For 85 example, the plunger 74 is adapted to engage and operate any one of ten pairs of spring-contacts 77, and to push the same outward and away from each other and into contact with the continuous contact-plates 78 and 79. 90 It will be readily understood that these spring-contacts are all suitably insulated from each other, and from the said contact-plates, and that the latter are insulated from each other. The plunger-point 75 is adapted 95 to engage and operate any one of ten pairs of spring-contacts 80, and to push the same into engagement with the continuous contact-plates 81 and 82. Fig. 7 is a perspective of a portion of one of said contact-plates, 100 and Fig. 8 is a perspective of one of said spring-contacts or switch-springs; and in Fig. 9, which is a view looking down into a portion of the bank, it will be seen that each pair of spring-contacts or switch-springs 105 presents a socket-like appearance, the ends of the springs being so formed as to accurately receive and guide the plunger-points in the right direction. It will be seen that each of the flexible spring-contacts of the bank is 110 provided at its rear end with a terminal whereby it may be soldered or otherwise connected to a circuit-wire. Each of the two continuous contact-plates is also provided with a suitable terminal, as shown in Fig. 7. 115 As stated, the flexible spring-contacts of each row are arranged in pairs between the two contact-plates allotted to such row, and with the arrangement shown the contacts and interposed strips of insulation are all clamped 120 tightly together by means of oppositely arranged and vertically-disposed clamping-plates 83 and 84, and by means of clamping-screws 85. With this arrangement, the plunger 73 is adapted, when the arm 67 is released, to be forced by the spring 64 into engagement with two pairs of spring-contacts in the two rows in the bank, thus simultaneously closing several circuits in the manner hereinafter more fully explained. The 125 130

bridge-cut-off-relay 86 is arranged in a horizontal position and secured by a screw 87 to a bracket 88, the latter being suitably secured to the side portion of the frame 51. An armature 89 is provided for the said bridge-cut-off-relay, said armature being pivotally mounted upon the bracket 88. In this way, the said armature has a horizontal axis 90 at the point where it is pivotally connected with the said bracket. In addition, the said armature is provided with an arm 91, and with a piece of insulation 92 mounted at the end thereof. The normally-closed switch-springs 93 and 94 are arranged one above the other and, together with suitable strips of interposed insulation, secured to the top of the bracket 88 by means of screws 95. In this way, the armature 89, when attracted, causes the insulation 92 to press the spring 93 out of engagement with the spring 94. In this connection, it will also be seen that the plunger-arm 67 has its shorter end portion provided with a finger 96 having a piece of insulation 97 adapted, when the said arm 67 is released, to engage and raise the spring 93 out of engagement with the spring 94. Consequently, the bridge-cut-off-springs 93 and 94 are adapted to be operated either by the relay-magnet 86, or by the "line-relay" 48, as will hereinafter more fully appear in connection with a description of the circuits and operation of the system. In a way, they are also operated by the "release-magnet" 55, inasmuch as the energizing and deenergizing of this magnet effects a restoration of the arm 67 to its normal position, and thereby a reclosing of the said springs 93 and 94. In practice, and by referring to Figs. 12 and 13, it will be seen that the subscribers' line-wires are connected to the two contact-plates represented by the conductors 81 and 82 of one row in the bank which comprises the spring-contacts 80, and which is, in fact, bank 76 (Fig. 6), while the pairs of spring-contacts between the two plates are each connected with a different trunk-line. Also, it will be seen that one of the plates in the other row is connected with one terminal of the "release-magnet" 55, while the other plate is grounded. Furthermore, in this second row of bank-contacts, one member of each pair of spring-contacts—the member which is adapted to make contact with the grounded plate—is connected with one of the contacts 15 of the step-by-step mechanism; but the other member of each pair—that is, the member adapted to make contact with the plate which is connected with the "release-magnet"—is connected with the release trunk-line-conductor of the corresponding trunk-line leading from the corresponding switch-spring or switch-socket in the other row. It will be understood that all the different electro-magnets, and the switch-springs op-

erated thereby, are provided with suitable terminals for making the necessary circuit connections therewith.

As shown in Fig. 14, the calling subscriber's line-wires 98 and 99 extend directly to the contact-plates 81 and 82, while the trunk-line-conductors 100 and 101 lead directly from the sixth pair of springs 80 to the condensers, 102 and 103 in the "connector" shown more in detail in Fig. 15. As previously stated, the first trunk-line selected by a calling subscriber can lead to a "first-selector," "second-selector," etc., according to the size of the exchange; or, if the exchange is comparatively small, the said trunk-line may lead directly to a "connector," as illustrated in Fig. 14. Referring to Figs. 12 and 14, it will be seen that the so-called "vertical" and "rotary" normals 104 and 105 lead from the calling subscriber's line, and may be assumed to be connected with the "vertical" and "rotary" bank-contacts of an ordinary "connector," whereby the calling subscriber's line may be called by some other subscriber through the medium of such "connector." On the other hand, the so-called "private-normal" 106 leads from one terminal of the calling subscriber's bridge-cut-off-relay 86 to the "private-bank-contact" corresponding to the "line-contacts" with which the normals 104 and 105 are connected in the said "connector" by which the calling subscriber's line is called by some other subscriber. In other words, the calling subscriber at station A calls out through the medium of his "individual-switch" and receives a call through the medium of the "connector" with which the said normals 104, 105 and 106 are connected; and this is done in the usual and well understood manner. In Fig. 2 the plate 14 is shown provided with a terminal 16. A different construction, for the sake of simplicity, which will accomplish the same end, is represented in Fig. 12. In the same figure the wiper 10 is provided with a terminal 16 which is, in fact, the terminal 16 shown in Fig. 2. It will be understood that when I say that in Fig. 12 the terminal 16 of the contact-plate in bank 11 is connected with one terminal of the "rotary-relay" 3, I mean that the wiper 10 takes the place of plate 14, and that the bank 11 is represented by the contacts 12; therefore, the non-grounded pole of the battery 107 is always electrically connected with the wiper 10; but in Fig. 12, and as a matter of convenience of illustration, this connection is shown as leading directly to the said wiper. As explained, the grounded pole of the battery is connected through the ground connections 108 and 109 with the plate 79 in the bank 76. On the other hand, however, the plate 78 in said bank is connected with the non-grounded pole of the battery through the medium of the series coils of 130

the "release-magnet" 55. Normally, the non-grounded pole of the battery is connected through the coils of the "line-relay" 48, and through the normally-closed contacts 93 and 94 with the "vertical-line-conductor" 98 of the calling subscriber's line. From the non-grounded pole of said battery a normally-open circuit leads through the coil of the "rotary-magnet" 2, through the normally-closed interrupter-springs 35 and 36, and thence through the normally-open relay-springs 47 to ground at 110, and thence from ground 108 to battery.

It will be readily understood that the other switches or switching machines employed in the system may be of any suitable, known or approved construction. For example, the "connector" shown in Fig. 14 as the medium through which the selected trunk-line is connected with the called subscriber's line, may be of the well-known form and construction shown in Fig. 15. This "connector" is of the form or type shown in Patent No. 815,176, granted March 13, 1906, to Keith, Erickson & Erickson, and will not need extensive description. As illustrated in Fig. 15, the said "connector" comprises the usual switch-shaft 111 mounted for both rotary and endwise step-by-step movements, and provided with the usual "private-wiper" 112, and also with the "line-wipers" 113 and 114. These wipers are adapted to cooperate with the "private-bank-contacts" 115, and the "line-bank-contacts" 116, in making the connections necessary for establishing connection between the trunk-line-conductors 100 and 101 and any subscriber's line terminating at contacts in the said banks. The said "connector" is also further identified by the old and well-known "vertical" and "rotary" "line-relays" 117 and 118, and by the so-called "back-release-relays" 119 and 120. The "connector" as shown also comprises the usual "vertical" and "rotary" magnets 121 and 122, together with the well-known "private-magnet" 123 and the "release-magnet" 124. Said "vertical" and "rotary" magnets are adapted to operate the switch-shaft through the medium of the usual ratchet or step-by-step devices, while the said "private-magnet" is adapted to operate the "side-switch-wipers" 125, 126, 127 and 128 in the usual and well-understood manner. As is customary in a "connector" of this character, a ringer-relay 129 is provided for enabling the calling subscriber to connect the called subscriber's line with the ringing-generator 130 after the "connector" has established the desired connection. The details of construction may be of the character fully shown and described in said patent, and the character of the circuits and the operation of the different devices shown in Fig. 15 will be more easily understood in connection with

the hereinafter described operation of connecting the calling subscriber's line with the called subscriber's line.

The subscribers' apparatus, both for talking and signaling, and also for calling or performing the switching operations which bring about the actuation of the "individual" and other automatic switches at the central station or exchange, may be of any suitable, known or approved character. In Fig. 14, the calling subscriber's apparatus A is the same as the called subscriber's apparatus B, and consequently a description of the former will suffice for both. The apparatus at sub-station A comprises a suitable transmitter 131 arranged in a normally-open local circuit including a local battery 132 and one winding 133 of the usual induction-coil. This local battery circuit for the transmitter is maintained in a normally-open condition by the normally-separated switch-springs 134 and 135, the latter being adapted to be operated by the insulation 136 carried by the switch-hook 137. The receiver 138 has one terminal connected with the switch-contact 139 of the calling switch-key 140, while the other terminal of said receiver is connected through a normally-open connection with the switch-contact 141 of the calling switch-key 142; it being observed that this connection includes the normally-closed switch-contacts 143, and the normally-open switch-contacts 144, and also the other winding 145 of the said induction-coil. The key or button 146 has another contact 147 with which it is normally out of engagement. This contact 147 is permanently connected with the two contacts 148 and 149 of the calling switch-keys 140 and 142, and also with the normally-disengaged switch-spring 150, as well as with the normally-disengaged switch-spring 151. The switch-hook is provided with a piece of insulation 152 for operating the springs 151 and 153, the latter being grounded at 154. The said switch-hook is also provided with a metal portion 155 adapted to normally engage the spring 156 and thereby normally connect the bell 157 in bridge across the subscriber's line. A portion 158 carried by the switch-hook, and insulated therefrom, is employed for operating the spring-contact 159, and for thereby pressing the three springs 159, 160 and 150 together when the receiver is replaced upon the hook. The construction is such, however, that when the receiver is removed, and the switch-hook rises, these three springs operated by the projection 158 are not pressed together. The construction is also of such character that when the hook is depressed it closes together the said three springs before opening or separating the springs 151 and 153. As will hereinafter more fully appear, the switch-keys 140 and 142 may be employed by the subscriber for

calling the desired number, while the button or key 146 can be employed for ringing the bell at the called subscriber's station. The three springs 159, 160 and 150, however, are 5 employed merely for the purpose of effecting the automatic release of the switches along the "line-circuit" as soon as the calling subscriber hangs up his receiver.

The manner of using the apparatus thus 10 shown, and the method of connecting the calling subscriber's line with the called subscriber's line, are as follows: The subscriber at station A removes the receiver from the switch-hook 137, thereby closing the local 15 circuit of the transmitter, and also closing the connection from ground 154 to the switch-points 148 and 149. After this, the said subscriber presses the switch-key 142, the required number of times, according to 20 the character of the first digit of the called subscriber's number. This completes a grounded circuit from ground 154 through the contact 149 and the "vertical-line-conductor" 98, through the springs 93 and 94 25 of the bridge-cut-off-relay of the subscriber's "individual-switch", through the "line-relay-coils" 48, and thence to the non-grounded pole of the battery 107. The said "line-relay-coils", when thus energized, cause their 30 cores to attract the armature 68, and to thereby effect a withdrawal of the armature-catch 69 from the end of the plunger-arm 67. When this is done, the spring 64 presses the plunger 73 into engagement with the 35 contacts in the bank 76. As the two pointed ends of the plunger enter the bank, four connections are established; first, the lines 98 and 99 leading from the calling subscriber's telephone are connected with the 40 trunk-line-conductors 100 and 101 leading to the next switch. This is done by the plunger-point 75. The other plunger-point 74 enters the other row of contacts in the bank, and thereby closes contact between the 45 release trunk-line-conductor 161 and the conductor 162 leading to the "release-magnet" 55, the circuit from this point to the non-grounded pole of the battery being completed by the conductor 163, thus preparing 50 the "release-circuit" for use later on when it is desired to release the switches. This second plunger-point also closes the circuit from ground at 109 to the bank-multiple-wire 164 leading to the bank-contact 12^a of 55 the shaft-rotating mechanism. The wiper 10 of the said shaft-rotating mechanism is always in line with the idle plungers of the different "individual-switches"—that is, the master switch wiper 10 is always maintained 60 in engagement with the bank contact 12 which corresponds to the individual switch bank opposite which all idle plungers are resting, and since the bank contact 12^a is allotted to the bank terminal just seized by 65 the plunger 73, the wiper 10 will be resting

upon this particular contact at this time. Consequently, a circuit will be closed from ground at 109 through the bank-springs to the conductor 164, through bank-contact with which wiper 10 is engaged, wiper 10, 70 conductor 166 and "rotary-relay" 3 to the non-grounded pole of the battery. As the armature of relay 3 is attracted, it closes circuit from ground 110 through the interrupter springs 35 and 36, and through rotary 75 magnet 2 to the non-grounded pole of the battery. This having been accomplished, the said "rotary-magnet" is immediately energized, and in attracting its armature causes the main shaft, through the medium of the 80 ratchet mechanism, to make another step, thus carrying the wiper 10 to the next adjacent contact. The said wiper will remain upon this latter contact, providing, of course, that this contact does not correspond to a 85 trunk-line which is already in use; for in such case this contact would be connected to ground, and the circuit being thus maintained through the "rotary-magnet", the step-by-step mechanism will be continued in 90 operation until the wiper arrives at a non-busy contact. Obviously, however, and while all this is happening, several other things have occurred. For example, as the plunger-arm 67 was released, the arm 96 95 caused the insulation 97 to engage the spring 93, thereby separating this spring from the spring 94, and thus opening the circuit through the "line-relay" 48. In this way, the calling subscriber's "line-circuit" is made 100 free from bridges; and in addition the releasing of the plunger-arm 67 is accomplished so quickly that a portion of the first or initial impulse transmitted over the "line-circuit" by the calling device is communicated to the "vertical-trunk-line-conductor" 100, and thence on to the next switch, the latter in this way being practically operated by the same momentary grounding of the subscriber's line at the sub-station. In other words, the first number-impulse projected onto the "line-circuit" by the calling subscriber is sufficient to operate both the "individual-switch" and give the next switch, as, for example, the "connector", the desired operation in accordance with the first impulse necessary for producing the operation corresponding to the first digit of the called number. In this way, it is only necessary 110 for the calling subscriber to start the calling operation, inasmuch as the first impulse incident to the operation of the calling device is sufficient to operate the "individual-switch" and thereby make the preliminary connection necessary for putting the subscriber's line in communication with the switch to be employed for performing an operation corresponding to the first digit of the called number. After getting connection with the 115 next switch, as, for example, a "first-se- 120

lector" or a "connector"—a "connector" being shown in the drawings—the calling subscriber can then operate his calling device in such manner as to produce the desired operation on the part of the said "connector".

The restoration of the switches may be accomplished in the usual manner—that is to say, simply by hanging up the receiver at the calling subscriber's station. This, of course, grounds both sides of the line at the sub-station, and thereby energizes the two "line-relays" 117 and 118 of the "connector". This having been accomplished, the springs 168 are brought together, thereby connecting the "connector" to ground at 169, and thus affording a circuit from the grounded pole of the battery through the "connector", back through the conductor 161, through the bank-springs held together by the plunger-point 74, through the "release-magnet" 55, and through the conductor 163 to the non-grounded pole of the battery. The said "release-magnet", being thus energized, attracts its armature 61, thereby causing the upper end portion 69 of the armature 68 to engage the end of the arm 67. As soon as the magnet 55 is deenergized, the spring 64^a then retracts the armature 61, and in so doing causes the armature 68 to pull the arm 67 into its normal position. When thus restored to its normal position, the arm 67 causes the plunger 73 to engage the portion 8 of the shaft 1, so as to bring the said plunger immediately into line with all other idle plungers of the different "individual-switches". In this way, the restoration of an "individual-switch" is accompanied by a selective action on the part of its plunger, providing, of course, that the said shaft 1 has been rotated to a different position during the time that the plunger 73 was in use.

When another subscriber calls the line running to station A, it is evident that the "connector" employed for so doing completes a circuit from ground 170 through the "side-switch-wiper" 126, through the "private-wiper" 112, thence through one of the bank-contacts 115 over the "private-normal" 106, through the bridge-cut-off relay 86, and thence to the non-grounded pole of the battery by way of the conductor 163. In this way, the bridge including the "line-relay" 48 is opened up or cut off when a subscriber calls the sub-station A, as well as when a subscriber at this station attempts to call some other subscriber. In one case the bridge-cut-off is operated electrically by the energizing of the bridge-cut-off-relay-coil, while in the other case it is operated mechanically by the releasing of the plunger-arm 67. This is shown in Fig. 14, where it will be seen that the bridge-cut-off-relay 86 is deenergized, the bridge-cut-off being held open by the insulation 97 carried by the arm 67; and in the "individual-switch" al-

lotted to the called subscriber's line, the bridge-cut-off-relay 171 is energized, thereby opening the bridge across the circuit including the "line-relay" 172. With this arrangement, the normally bridged "line-relay" of 70 an "individual-switch" is advantageously gotten rid of each time the subscriber calls or is called.

The manner of operating the "connector," and of ringing the bell at the called subscriber's station, will be readily understood, and will need no detailed explanation. The subscriber's calling device can be of any suitable character; but as shown, the key 142 is employed for operating the "individual-switch," and for operating the "vertical-relay" of the "connector." The key 140 is employed for energizing the so-called "rotary-relays" of the "selectors" or of the "connector," as the case may be, and for 80 thereby operating the "side-switch" of the "selector" and the "connector," in the usual and well-known manner. With the arrangement shown, for example, the operation of the key 142 brings about the desired automatic operation on the part of the "individual-switch," and also produces the requisite or desired vertical step-by-step movement on the part of the switch-shaft 111 of the "connector." A single impulse then 90 transmitted by means of the key 140 over the other side of the circuit, energizes the "rotary-relay" 118, and thereby accomplishes a closing of the local or internal circuit including the "private-magnet" 123. 100 This, of course, gives the "side-switch" one forward step—from the first to second position—and puts the "connector" in position to receive the next impulse or impulses transmitted by the key 142. This time, however, the impulse or impulses transmitted over the so-called "vertical-line-conductor" of the circuit brings about the energizing of the "rotary-magnet" 122, the "side-switch-arm" 125 having been shifted into 110 position to close circuit at this point through the said "rotary-magnet." In this way, the calling subscriber rotates the shaft 111 until the wipers thereon arrive at the contacts corresponding to the line of the called subscriber. After this, the single impulse transmitted by the key 140 effects the final movement of the "side-switch" from second to third position, thus establishing connection between a trunk-line and the called subscriber's line. 115

The means for transmitting the impulses which correspond to the number of the called subscriber, and which accomplish the desired operations on the part of the "individual" and other switches, is called a calling device for the reason that it is employed by the calling subscriber for electrically calling the number of the other subscriber. The bell at each sub-station is, of 120

course, a call signal, but these and the push-buttons or switches for operating them are distinguished from the calling devices by reference thereto as the means for ringing 5 the called subscriber.

It will be seen that each subscriber has control of his particular or allotted "individual-switch" for connective purposes only—that is, he cannot bring about any selective action on the part of his "individual-switch." Each subscriber is, however, given means whereby he may cause his "individual-switch" to close the connection which it has already selected, and whereby he may at the 10 same time cause all idle "individual-switches," of his particular group, to select the next idle trunk-line. In this way, each subscriber always finds his "individual-switch" ready and in position to establish 15 connection with an idle trunk-line, providing, of course, that all of the trunk-lines allotted to a group of subscribers are not busy at the same time. Each subscriber has control over his particular "individual-switch" 20 for connective purposes, and in addition has control over all idle "individual-switches," other than his own, for selective purposes only. Consequently, each subscriber is given 25 an "individual-switch" of such character 30 that it can quickly make the desired preliminary connection without resorting to any selective operation or searching through the different trunk-lines, and of such character that, when put in use, it automatically 35 and instantly causes the switch-operating machine to produce a selective operation on the part of all idle "individual-switches" in the same group. With this arrangement, no 40 subscriber can use his "individual-switch" without automatically advancing all idle "individual-switches" in the same group to a position where each is ready to respond instantly to its allotted subscriber for the 45 purpose of establishing connection with an idle trunk-line. By thus providing each subscriber with an "individual-switch" which is always ready and in condition, when the subscriber desires to call some other subscriber, to establish connection with a previously 50 selected idle trunk-line, it is evident that the first number-impulse transmitted by the calling device, or that the first impulse brought about by the initial movement or operation of the calling device, is amply 55 sufficient to operate both the "individual-switch" and the "selector" or "connector" or other switch next in line for operation. In other words, the "individual-switch" can be operated by the first number-impulse intended 60 for producing the initial operation of a "selector," "connector" or other similar switch, and without in any way interfering with the necessary or desired operation on the part of the latter. Obviously, the initial 65 impulse, or first number-impulse as it may

be called, transmitted over the "line-circuit" causes the "individual-switch" of the calling subscriber to establish connection with the previously selected idle trunk-line; and this operation is accomplished so quickly that 70 before the current-flow ceases—that is, before the momentary connection to ground at the calling subscriber's station is opened—the "selector" or "connector" or other switch next in line for operation, and for which the 75 impulse is also intended, is in electrical communication with the calling subscriber's line, and is given the desired actuation or initial operation by the flow of current through the new circuit established from the 80 non-grounded pole of the battery through the "selector" or "connector," or other switch, over one side of the trunk-line and through the "line-contacts" of the "individual-switch," and thence over one side of 85 the subscriber's line to the ground connection which is still closed. When an "individual-switch" is released, its plunger will simply withdraw from engagement with the particular bank-contacts employed for making the connection, and will return to normal engagement with the shaft 8, whereby the plunger 73 is automatically placed in the same selective position as the remaining 90 idle plungers. In this way, the release of each "individual-switch" is accompanied by the automatic selection on the part of its plunger of another trunk-line, and of a trunk-line which is, of course, idle or out of use at the time the release is made. Preferably, and with the arrangement shown, each plunger is, when released from its bank of contacts, automatically brought into alignment with all plungers which are idle at 95 that time. In this way, the idle plungers in 100 the group always occupy the same switching position, and are made to advance in unison from one switching position to another as fast as the different "individual-switches" are successively put into use. If there are 110 fifty subscribers in the group, it is evident that only ten of these subscribers can use their "individual-switches" at the same time; but in practice I find that for ten subscribers to be using their individual switches 115 at the same time is not likely to occur, and that it is even possible to include one hundred subscribers in a group having but ten outgoing trunk-lines—that is, trunk-lines by which their "individual-switches" may be 120 employed for getting connection with a "first-selector" or "connector" or other switch, as the case may be. If there are one hundred subscribers in the group, and five subscribers are using their "individual-switches" at the same time, it is evident that the plungers of these five switches will all 125 occupy different switching positions, so that each subscriber may have a different outgoing trunk-line; but it is also evident that the 130

remaining ninety-five idle "individual-switches" will all have their plungers lined up and held in the same switching position by reason of their engagement with the angularly-shaped portion 8 of the shaft 1. Should another subscriber decide to use his "individual-switch," the plunger thereof will establish connection between his line and the idle trunk-line at which all of the other 5 idle subscribers' plungers have been waiting, thus causing all idle plungers to again advance in unison to a new and idle switching position. It is evident, therefore, that each plunger is subject to only connective operations 10 on the part of its allotted subscriber, but is subject to only selective operations on the part of any other subscriber in the same group. No subscriber can use his "individual-switch" without advancing all other "individual-switches" in the same group to an 15 idle switching position, and no subscriber can release his "individual-switch" without causing the plunger thereof to automatically swing itself into a position corresponding to 20 the switching position at that time occupied by all other idle plungers. Each subscriber's "individual-switch," when he is not using it, is always ready and in waiting to close connection with an idle trunk-line, and the calling 25 subscriber has but to trip the circuit-closing means of his "individual-switch" in order to cause the latter to close the already or previously selected idle trunk-line connection.

30 It will be seen that the mechanism of the master switch, or the switch-operating machine as it may be called, constructed, for example, as shown in Fig. 2, constitutes an automatic means or mechanism for selecting 35 idle talking trunks ahead of the calls—that is to say, for selecting idle trunks for the calling subscribers. In this way a common mechanism is provided for selecting the 40 idle trunks, and the subscribers are provided with individual devices for seizing the preselected idle trunks. With this arrangement each calling subscriber merely operates his individual switch or device for the purpose of seizing the preselected trunk, and at 45 the same time causes the common trunk-selecting mechanism to step forward and thereby select a new or different trunk for the subscriber who makes the next call. It will also be seen that the plungers 74 serve 50 as swinging and endwise-movable members for traversing the series of trunks, and for engaging and seizing a preselected idle trunk. Preferably, as shown and described, these plungers or step-by-step operated 55 60 swinging members 74 are excluded from the talking circuits, but this may be modified without departing from the broader purposes of my invention. It will be seen that these plungers or swinging members 74 are

given a step-by-step movement from one 65 trunk to another, so that when not in use for talking purposes, each plunger or swinging member is in alignment with an idle trunk, and is thus waiting to respond to the calling subscriber for the purpose of seizing 70 such trunk. As shown and described, the said plungers or swinging step-by-step operated members 74 are normally out of engagement with the trunk terminals, but this may also be modified or changed without 75 departing from the broader purposes of my invention. In this way, as stated, I provide a common mechanism for selecting idle trunks ahead of the calls, and provide a plurality of traveling members which 80 traverse the trunk line terminals while not in use for talking purposes, and which are adapted to engage or seize the preselected trunks in response to calling subscribers.

What I claim as my invention is:

1. A telephone system comprising a calling subscriber's line, trunk lines, an "individual-switch" adapted for use by the calling subscriber to connect with any one of a number of said trunk lines, provided with 85 a swinging and endwise-movable plunger for closing connection between said line and an idle one of said trunk-lines, and a talking circuit excluding said plunger.

2. A telephone system comprising a calling subscriber's line, a plurality of trunk-lines, and an "individual-switch" capable of connecting the subscriber's line with any one of said trunk-lines, provided with a laterally and endwise movable plunger, always ready and in position to connect the subscriber's line with an idle trunk-line while the said switch is not in use.

3. A telephone system comprising a calling subscriber's line, an "individual-switch" allotted to said line, a plurality of trunk-lines leading from said switch, the latter being capable of establishing connection between the subscriber's line and any one of said trunk-lines, provided with a laterally and endwise movable plunger always in position to establish connection with an idle trunk-line while the subscriber's line is not in use.

4. A telephone system comprising a subscriber's line, a plurality of trunk-lines, a switching device capable of establishing connection between said subscriber's line and any one of said trunk-lines, and provided with a laterally and endwise movable plunger for searching for an idle trunk-line while the subscriber's line is not in use, but always ready and in position to complete a connection with an idle trunk-line while the switch is not in use.

5. A telephone system comprising a plurality of subscribers' lines, a plurality of trunk-lines allotted to and common to said

subscribers' lines, but less in number than the said subscribers' lines, together with an "individual-switch" for each subscriber's line, and means common to all of said subscribers' lines for operating said switches, each switch being provided with a laterally and endwise movable plunger for establishing connection with any one of said trunk-lines, always ready and in position to establish connection with an idle trunk-line while the subscriber's line is out of use.

6. A telephone system comprising a plurality of subscribers' lines, a plurality of trunk-lines less in number than the subscribers' lines, an "individual-switch" for each subscriber's line, and a switch-operating means common to all of said subscribers' lines and adapted for selectively operating said switches, each "individual-switch" being capable of establishing connection with any one of said trunk-lines, and said switch-operating means being normally and mechanically connected with all idle switches, but entirely disconnected from all busy switches, whereby no switch is operated by said means except while out of use and when some other switch is put in use.

7. A telephone system comprising a switch, said switch including a plurality of trunk-line-terminals, a pair of subscriber's line-terminals arranged at opposite sides of said row of trunk-line-terminals, each trunk-line-terminal consisting of a pair of switch-springs, and automatic means for selecting an idle trunk-line, and a laterally and endwise movable plunger for forcing the terminal-springs of such idle trunk-line into engagement with the said subscriber's line-terminals.

8. A telephone system comprising a plurality of subscribers' lines, an "individual-switch" for each subscriber's line, each switch provided with a laterally and endwise movable plunger, a plurality of trunk-lines less in number than the subscribers' lines and each connected with all of said switches, automatic means for enabling any switch when put in use to cause any and all idle plungers to select the next idle trunk-line, each switch when out of use always ready and in position to establish connection between its allotted subscriber's line and a preselected idle trunk-line.

9. A telephone system comprising a plurality of subscribers' lines, an "individual-switch" for each subscriber's line, each switch provided with a laterally and endwise movable plunger, a plurality of trunk-lines less in number than the subscribers' lines and each connected with all of said switches, and electrically-operated automatic means for enabling each switch when put in use to cause any and all idle plungers

to select the next idle trunk-line, each switch when not in use always ready and in position to establish connection with a preselected idle trunk-line.

10. A telephone system comprising a subscriber's line provided with stationary terminals, a plurality of flexible trunk-line-terminals each adapted to be forced into contact with said subscribers' line-terminals, other subscribers' lines having similar line-terminals, other trunk-line-terminals connected with the same trunk-lines and associated with said other subscribers' line-terminals, a circuit-closing plunger for each subscriber's line, and automatic means whereby each plunger is, when not in use, always ready and in position to establish connection between its allotted subscriber's line and a preselected idle trunk-line.

11. A telephone system comprising a plurality of subscribers' lines, a plurality of trunk lines less in number than the said subscribers' lines, an individual switch for each subscriber's line, each trunk line being connected with all of said switches, the said switches being each provided with a traveling trunk selector and circuit-closing device capable of establishing connection between its allotted subscribers' lines and any one of said trunk lines, and the system also comprising automatic means whereby said circuit-closing device when put in use causes any and all idle devices to simultaneously select an idle trunk line, each said device when in use always ready and in position to establish connection between its allotted subscribers' lines and the pre-selected one of said trunk lines.

12. A telephone system comprising a subscriber's line, a subscriber's calling device, preliminary automatic switching means adapted to respond to the first electrical impulse produced by the operation of said calling device, and additional switching means also adapted to respond to said first impulse and to perform switching operations corresponding to all digits of the called number in response to additional electrical impulses produced by the said calling device subsequent to the operation of said preliminary automatic switching means.

13. A telephone system comprising a subscriber's line, a subscriber's calling device, automatic switching means adapted to perform a trunking operation in response to the first electrical impulse produced by the operation of said device in calling the desired number, and a step-by-step selective switching machine adapted to perform an operation corresponding to the first digit of the called number and in response to an impulse or impulses produced by the said calling device.

14. A telephone system comprising a plu-

rality of subscribers' lines, a plurality of trunk-lines less in number than the said subscribers' lines, an "individual-switch" for each subscriber's line, each "individual-switch" being capable of establishing connection between its allotted subscriber's line and any one of said trunk-lines, a switch-operating means only normally in operative connection with all of said switches, each 5 switch when idle being always ready and in position to establish connection with an idle trunk-line, and automatic means adapted and operative to cause said switch-operating means to advance any and all idle "individual-switches" to the position necessary for establishing connection with the next idle trunk-line upon the mechanical disconnection of any switch from said switch-operating means and the consequent establishment 10 of a connection between one of said trunk-lines and the subscriber's line to which the said busy switch is allotted.

15. A telephone system comprising a plurality of switches, a switch-operating means common to all of said switches and normally connected with the latter, and automatic means adapted and operative to cause said switch-operating means to bring about a selective operation on the part of any and all 20 idle switches upon the total mechanical disconnection of any switch from the said switch-operating means.

16. A telephone system comprising a plurality of switches, each switch provided with 25 a laterally and endwise movable plunger, a switch-operating means common to all of said switches and adapted for bringing about only selective operations on the part of said plungers, each switch including 30 within itself suitable means for then effecting a closure of any connection which its plunger is caused to select by the said switch-operating means, and automatic means whereby the closure of any connection 35 by any switch plunger causes any and all idle plungers to simultaneously select the next idle connection, said switches being electrically connected together and thus each adapted for closing and establishing any one 40 of a certain number of normally-open electrical connections.

17. A telephone system comprising a subscriber's line, a plurality of trunk-lines to be used by said subscriber in calling other 45 subscribers, means whereby the same trunk-lines may be used by other subscribers, automatic circuit-closing means capable of establishing connection between the said subscriber's line and any one of said trunk-lines, controllable by the said subscriber, provided with a laterally and endwise movable plunger, together with automatic means adapted and operative to produce a selective operation on the part of said circuit-closing means while the latter are idle and 50

each time one of said trunk-lines is temporarily appropriated for use by some other subscriber.

18. A telephone system comprising a plurality of subscribers' lines, a plurality of trunk-lines less in number than the subscribers' lines, an "individual-switch" for each subscriber's line, and a switch-operating means common to all of said switches and normally connected with the same, but 70 only capable of producing selective operations on the part of said switches, said switches being suitably electrically connected together and thereby each adapted for establishing connection between its allotted subscriber's line and any one of said trunk-lines, and each switch comprising means under the control of its allotted subscriber for entirely and mechanically disconnecting it from the said switch-operating means and establishing connection with the idle trunk-line automatically selected while the switch is out of use, and the said switches and switch-operating means as a whole comprising automatic means adapted and operative, upon the closing of connection between any subscriber's line and one of said trunk-lines, to cause said switch-operating means to bring about a selective operation on the part of any and all idle switches, whereby 85 each switch is, when not in use, always ready and in position to establish connection with a preselected idle trunk-line.

19. A telephone system comprising a subscriber's line, a plurality of trunk-lines, switch-springs arranged in pairs and adapted for establishing connection between said subscriber's line and said trunk-line, a switch-spring-operator, automatic means for moving said switch-spring-operator from 100 one pair of springs to another, while the subscriber's line is not in use, and means under the control of the subscriber and including a "line-relay" for causing said switch-spring-operator to engage the pair of switch-springs corresponding to the idle trunk-line previously selected by the said switch-spring-operator while out of use.

20. A telephone system comprising normally open circuit connections, a switch provided with a laterally and endwise movable plunger subject to selective operations while out of use, and including means under the control of a subscriber for closing any normally-open circuit connection selected by the 115 plunger while out of use.

21. A telephone system comprising an automatic "individual-switch" provided with a laterally and endwise movable plunger controllable by a certain subscriber for connective purposes only, but also controllable by other subscribers for selective purposes only.

22. A telephone system comprising an automatic "individual-switch" provided with 130

5 a laterally and endwise movable plunger controllable by a certain subscriber for connective purposes only, but also controllable, when idle or out of use, by one or more other subscribers for selective purposes only.

23. A telephone system comprising a "line-relay," a pivoted plunger-arm, a "line-relay-armature" adapted to hold said plunger-arm in its normal position, a bank of contacts, a plunger pivotally mounted upon the end of said arm and provided with means for engaging and closing together said contacts, a "release-magnet" and means whereby the energizing and deenergizing of the same restores the said arm to its normal position, the said relay when energized being adapted to attract its armature and thereby release the said arm and cause the said plunger to engage said contacts, together with automatic means for swinging said plunger about its pivotal point while the switch is out of use, and whereby the said switch is controllable by a certain subscriber for connective purposes only.

24. A telephone system comprising a subscriber's "line-relay," a bank of switch-contacts, a plunger for operating said contacts, means whereby the energizing of said "line-relay" causes said plunger to engage said contacts, and automatic means for causing said plunger to move along in front of said contacts while said "line-relay" remains deenergized.

25. A telephone system comprising a circuit-closing plunger controllable by a certain subscriber for connective purposes only, but also controllable, when out of use, by one or more other subscribers for selective purposes only.

26. A telephone system comprising a plurality of switch-sockets and a circuit-closing plunger adapted to enter said sockets, together with means whereby said plunger is controllable by a certain subscriber for connective purposes only, and whereby said plunger, when out of use, is controllable by one or more other subscribers for selective purposes only, and a trunk-line for each socket.

27. A telephone system comprising a plurality of switching positions, a circuit-closing device provided with a laterally and endwise movable plunger controllable by a plurality of subscribers for automatically selecting an idle switching position, but only controllable by a certain subscriber for connective purposes, and a line leading from each position.

28. A telephone system comprising a plurality of "individual-switches," and a switch-operating machine common to and normally connected with all of said switches, each switch comprising a bank of contacts, a pivoted arm, a plunger pivotally mounted upon said arm and adapted to engage said

contacts, a "line-relay" provided with an armature adapted to hold said arm in its normal position, a "release-magnet" provided with an armature connected for operating the "relay-armature" and thereby restoring the arm to its normal position, and the said switch-operating machine comprising a rotatable member adapted to engage the plungers of all of said switches, together with automatic means whereby the energizing of the "line-relay" of any switch is accompanied by the operation of said switch-operating machine, and by the consequent swinging of all idle plungers about their axes.

29. A telephone system comprising an automatic switching apparatus provided with a plurality of pivoted plungers, means for operating the same for connective purposes, a rotatable member adapted to engage all of said plungers and swing the same about their axes for selective purposes only, and talking circuits excluding said plungers.

30. A telephone system comprising a plurality of pivoted plungers each controllable by one member of a certain group of subscribers for connective purposes only, but each controllable by all other subscribers in such group for selective purposes only.

31. A telephone system comprising a plurality of pivoted circuit-closing laterally and endwise movable plungers, and means controllable by all of the subscribers to whom the said plungers are allotted for producing a selective operation on the part of all idle plungers upon the use of any plunger for connective purposes.

32. A telephone system comprising a plurality of switches each provided with a pivoted circuit-closing laterally and endwise movable plunger, and a switch-operating machine provided with a rotatable member adapted normally to engage all of said plungers, normally inoperative connection with all of said plungers.

33. A telephone system comprising a plurality of pivoted circuit-closing laterally and endwise movable plungers, and a switch-operating machine normally in operative connection with all of said plungers, together with automatic means whereby the disconnection of any plunger from said machine for connective purposes produces a simultaneous selective operation on the part of any and all idle plungers.

34. A telephone system comprising a plurality of banks or contacts, a pivoted laterally and endwise movable plunger for each bank, means whereby each plunger may be operated for connective purposes independently of all other plungers, together with a rotatable member adapted to engage and rotate all idle plungers upon the use of any plunger for connective purposes.

35. A telephone system comprising a

3 ratchet device, an electro-magnet for actuating said ratchet device continuously in one direction, a bank of contacts, a switch-arm adapted to swing forward and back upon said contacts, so as to always engage one of said contacts, and transmitting connections for converting the continuous or one way rotation of said ratchet device into a forward and back movement on the part of said 10 switch-arm, said arm adapted to move step-by-step in unison with the ratchet device.

36. A telephone system comprising an electro-magnetically-actuated ratchet device adapted for continuous rotation in one direction, a bank of contacts, and a member for engaging said contacts, and always in contact therewith, together with means for converting the continuous or one-way rotary motion of said ratchet device into a reciprocating motion on the part of said member, said member adapted to have a step-by-step motion in one direction in unison with the ratchet device.

37. A telephone system comprising a bank 25 of contacts, a switch-arm adapted to move forward and back upon said contacts, a cam rigid with said arm, a rotary member provided with a plurality of pins adapted to engage said cam, electro-magnetically-actuated ratchet devices for rotating said rotary member, so as to cause said arm to move forward upon the said contacts, and spring means for quickly and automatically returning said arm to its normal position upon the 35 disengagement of said cam from one of said pins.

38. A telephone system comprising a plurality of switches each capable of establishing any one of a number of possible connections, manually-controlled means for causing any one of said switches to close a connection, and automatic means whereby each switch is released to perform a selective operation when its allotted subscriber hangs 40 up his telephone, and whereby each switch is always ready and in position to close a pre-selected idle or non-busy connection.

39. A telephone system comprising a switching machine capable of closing any 45 one of a number of possible connections, comprising automatic means whereby the said switch when released from use instantly assumes another switching position corresponding to the idle or non-busy connection 55 next in order after the one last in use.

40. The combination, in a subscriber-operated telephone and signaling system, of a calling subscriber's line, a plurality of trunk-lines, and an "individual-switch" capable of 60 connecting the subscriber's line with any one of said trunk-lines, provided with a laterally and endwise movable plunger always ready and in position to connect the subscriber's line with an idle trunk-line while the said 65 switch is not in use, manually-controlled

and electrically-operated means whereby a calling subscriber may produce an audible call-signal at the station of the called subscriber, and suitable telephonic transmitting and receiving instruments whereby the calling and called subscribers may converse with each other.

41. The combination, in a subscriber-operated telephone and signaling system, of a plurality of subscribers' lines, a plurality of trunk-lines less in number than the subscribers' lines, an "individual-switch" for each subscriber's line, and a switch-operating means common to all of said subscribers' lines and adapted for selectively operating said switches, each "individual-switch" being capable of establishing connection with any one of said trunk-lines, and switch-operating means being normally and mechanically connected with all idle switches, 75 but entirely disconnected from all busy switches, whereby no switch is operated by said means except while out of use and when some other switch is put in use, manually-controlled and electrically-operated 80 means whereby a calling subscriber may produce an audible call-signal at the station of the called subscriber, and suitable telephonic transmitting and receiving instruments whereby the calling and called 85 subscribers may converse with each other.

42. The combination, in a subscriber-operated telephone and signaling system, of a plurality of subscribers' lines, an "individual-switch" for each subscriber's line, each switch provided with a laterally and endwise movable plunger, a plurality of trunk-lines less in number than the subscribers' lines and each connected with all of said switches, automatic means for enabling 90 any switch when put in use to cause any and all idle plungers to select the next idle trunk-line, each switch when out of use always ready and in position to establish connection 95 between its allotted subscriber's line and a preselected idle trunk-line, manually-controlled 100 and electrically-operated means whereby a calling subscriber may produce an audible call-signal at the station of the called subscriber, and suitable telephonic 105 transmitting and receiving instruments whereby the calling and called subscribers 110 may converse with each other.

43. The combination, in a subscriber-operated telephone and signaling system, of a subscriber's line, a subscriber's calling device, preliminary automatic switching means adapted to respond to the first electrical impulse produced by the operation of said calling device, and additional switching means 115 also adapted to respond to said first impulse and to perform switching operations corresponding to all digits of the called number in response to additional electrical impulses 120 produced by the said calling device subse- 125 130

- quent to the operation of said preliminary automatic switching means, manually-controlled and electrically-operated means whereby a calling subscriber may produce 5 an audible call-signal at the station of the called subscriber, and suitable telephonic transmitting and receiving instruments whereby the calling and called subscribers may converse with each other.
- 10 44. The combination, in a subscriber-operated telephone and signaling system, of a plurality of switches, a switch-operating means common to all of said switches and normally connected with the latter, and 15 automatic means adapted and operative to cause said switch-operating means to bring about a selective operation on the part of any and all idle switches upon the total mechanical disconnection of any switch from 20 the said switch-operating means, manually-controlled and electrically-operated means whereby a calling subscriber may produce an audible call-signal at the station of the called subscriber, and suitable telephonic 25 transmitting and receiving instruments whereby the calling and called subscribers may converse with each other.
45. The combination, in a subscriber-operated telephone and signaling system, of an automatic "individual-switch" provided 30 with a laterally and endwise movable plunger controllable by a certain subscriber for connective purposes only, but also controllable by other subscribers for selective purposes only, manually-controlled and electrically-operated means whereby a calling subscriber may produce an audible call-signal 35 at the station of the called subscriber, and suitable telephonic transmitting and receiving instruments whereby the calling and called subscribers may converse with each other.
46. The combination, in a subscriber-operated telephone and signaling system, of an automatic switching apparatus provided 40 with a plurality of pivoted plungers, and means for operating the same for connective purposes, together with a rotatable member adapted to engage all of said plungers and 45 swing the same about their axes for selective purposes only, manually-controlled and electrically-operated means whereby a calling subscriber may produce an audible call-signal 50 at the station of the called subscriber, and suitable telephonic transmitting and receiving instruments whereby the calling and called subscribers may converse with each other.
47. The combination, in a subscriber-operated telephone and signaling system, of a plurality of switches each capable of establishing 55 any one of a number of possible connections, manually-controlled means for causing any one of said switches to close a connection, and automatic means whereby 60

each switch is released to perform a selective operation when its allotted subscriber hangs up his telephone, and whereby each switch is always ready and in position to close a preselected idle or non-busy connection, 70 manually-controlled and electrically-operated means whereby a calling subscriber may produce an audible call-signal at the station of the called subscriber, and suitable telephonic transmitting and receiving instruments whereby the calling and called subscribers may converse with each other.

48. In a subscriber-operated system of trunking and signaling, comprising means for telephoning over the trunk connections, the combination of a calling subscriber's line, a plurality of trunk-lines, and an "individual-switch" capable of connecting the subscriber's line with any one of said trunk-lines, provided with a laterally and endwise-movable plunger always ready and in position to connect the subscriber's line with an idle trunk-line while the said switch is not in use, a source of electric current at the exchange or central station for furnishing all current necessary for operating the switching means at the exchange by which one subscriber's line is connected with another, and another source of current at the central station or exchange and means operated thereby and controlled by a calling subscriber for producing an audible call-signal at the station of the called subscriber.

49. In a subscriber-operated system of trunking and signaling, comprising means for telephoning over the trunk connections, the combination of a plurality of subscribers' lines, a plurality of trunk-lines less in number than the subscribers' lines, an "individual-switch" for each subscriber's line, and a switch-operating means common to all of said subscribers' lines and adapted for selectively operating said switches, each "individual-switch" being capable of establishing connection with any one of said trunk-lines, and said switch-operating means being normally and mechanically connected with all idle switches, but entirely disconnected from all busy switches, whereby no switch is operated by said means except while out of use and when some other switch is put in use, a source of electric current at the exchange or central station for furnishing all current necessary for operating the switching means at the exchange by which one subscriber's line is connected with another, and another source of current at the central station or exchange and means operated thereby and controlled by a calling subscriber for producing an audible call-signal at the station of the called subscriber.

50. In a subscriber-operated system of trunking and signaling, comprising means for telephoning over the trunk connections, the combination of a plurality of subscribers' 130

lines, an "individual-switch" for each subscriber's line, each switch provided with a laterally and endwise movable plunger, a plurality of trunk-lines less in number than the subscribers' lines and each connected with all of said switches, automatic means for enabling any switch when put in use to cause any and all idle plungers to select the next idle trunk-line, each switch when out of use always ready and in position to establish connection between its allotted subscriber's line and a preselected idle trunk-line, a source of electric current at the exchange or central station for furnishing all current necessary for operating the switching means at the exchange by which one subscriber's line is connected with another, and another source of current at the central station or exchange and means operated thereby and controlled by a calling subscriber for producing an audible call-signal at the station of the called subscriber.

51. In a subscriber-operated system of trunking and signaling, comprising means for telephoning over the trunk connections, the combination of a subscriber's line, a subscriber's calling device, preliminary automatic switching means adapted to respond to the first electrical impulse produced by the operation of said calling device, and additional switching means also adapted to respond to said first impulse and to perform switching operations corresponding to all digits of the called number in response to additional electrical impulses produced by the said calling device subsequent to the operation of said preliminary automatic switching means, a source of electric current at the exchange or central station for furnishing all current necessary for operating the switching means at the exchange by which one subscriber's line is connected with another, and another source of current at the central station or exchange and means operated thereby and controlled by a calling subscriber for producing an audible call-signal at the station of the called subscriber.

52. In a subscriber-operated system of trunking and signaling, comprising means for telephoning over the trunk connections, the combination of a plurality of switches, a switch-operating means common to all of said switches and normally connected with the latter, and automatic means adapted and operative to cause said switch-operating means to bring about a selective operation on the part of any and all idle switches upon the total mechanical disconnection of any switch from the said switch-operating means, a source of electric current at the exchange or central station for furnishing all current necessary for operating the switching means at the exchange by which one subscriber's

line is connected with another, and another source of current at the central station or exchange and means operated thereby and controlled by a calling subscriber for producing an audible call-signal at the station of the called subscriber.

53. In a subscriber-operated system of trunking and signaling, comprising means for telephoning over the trunk connections, the combination of an automatic "individual-switch" provided with a laterally and endwise movable plunger controllable by a certain subscriber for connective purposes only, but also controllable by other subscribers for selective purposes only, a source of electric current at the exchange or central station for furnishing all current necessary for operating the switching means at the exchange by which one subscriber's line is connected with another, and another source of current at the central station or exchange and means operated thereby and controlled by a calling subscriber for producing an audible call-signal at the station of the called subscriber.

54. In a subscriber-operated system of trunking and signaling, comprising means for telephoning over the trunk connections, the combination of an automatic switching apparatus provided with a plurality of pivoted plungers, and means for operating the same for connective purposes, together with a rotatable member adapted to engage all of said plungers and swing the same about their axes for selective purposes only, a source of electric current at the exchange or central station for furnishing all current necessary for operating the switching means at the exchange by which one subscriber's line is connected with another, and another source of current at the central station or exchange and means operated thereby and controlled by a calling subscriber for producing an audible call-signal at the station of the called subscriber.

55. In a subscriber-operated system of trunking and signaling, comprising means for telephoning over the trunk connections, the combination of a plurality of switches each capable of establishing any one of a number of possible connections, manually-controlled means for causing any one of said switches to close a connection, and automatic means whereby each switch is released to perform a selective operation when its allotted subscriber hangs up his telephone, and whereby each switch is always ready and in position to close a preselected idle or non-busy connection, a source of electric current at the exchange or central station for furnishing all current necessary for operating the switching means at the exchange by which one subscriber's line is connected with another, and another source of current at the central station or exchange and means

operated thereby and controlled by a calling subscriber for producing an audible call-signal at the station of the called subscriber.

56. The combination, in an automatic or subscriber-operated telephone system of the trunk-release type, of a calling subscriber's line, a plurality of trunk-lines, and an "individual-switch" capable of connecting the subscriber's line with any one of said trunk-lines, provided with a laterally and endwise movable plunger always ready and in position to connect the subscriber's line with an idle trunk-line while the said switch is not in use, local "release-circuits" at the central station or exchange for effecting a release of any switch or switches employed thereat for establishing connection between a calling and a called subscriber's line, suitable "line-circuits", and means whereby the closure of a local circuit and the consequent release of a switch or switches is initiated by a subscriber over a "line-circuit".

57. The combination, in an automatic or subscriber-operated telephone system of the trunk-release type, of a plurality of subscribers' lines, a plurality of trunk-lines less in number than the subscribers' lines, an "individual-switch" for each subscriber's line, and a switch-operating means common to all of said subscribers' lines and adapted for selectively operating said switches, each "individual-switch" being capable of establishing connection with any one of said trunk-lines, and said switch-operating means being normally and mechanically connected with all idle switches, but entirely disconnected from all busy switches, whereby no switch is operated by said means except while out of use and when some other switch is put in use, local "release-circuits" at the central station or exchange for effecting a release of any switch or switches employed thereat for establishing connection between a calling and a called subscriber's line, suitable "line-circuits", and means whereby the closure of a local circuit and the consequent release of a switch or switches is initiated by a subscriber over a "line-circuit".

58. The combination, in an automatic or subscriber-operated telephone system of the trunk-release type, of a plurality of subscribers' lines, an "individual-switch" for each subscriber's line, each switch provided with a laterally and endwise movable plunger, a plurality of trunk-lines less in number than the subscribers' lines and each connected with all of said switches, automatic means for enabling any switch when put in use to cause any and all idle plungers to select the next idle trunk-line, each switch when out of use always ready and in position to establish connection between its allotted subscribers' line and a preselected idle trunk-line, local "release-circuits" at the central station or exchange for effecting a

release of any switch or switches employed thereat for establishing connection between a calling and a called subscriber's line, suitable "line-circuits", and means whereby the closure of a local circuit and the consequent release of a switch or switches is initiated by a subscriber over a "line-circuit".

59. The combination, in an automatic or subscriber-operated telephone system of the trunk-release type, of a subscriber's line, a subscriber's calling device, preliminary automatic switching means adapted to respond to the first electrical impulse produced by the operation of said calling device, and additional switching means also adapted to respond to said first impulse and to perform switching operations corresponding to all digits of the called number in response to additional electrical impulses produced by the said calling device subsequent to the operation of said preliminary automatic switching means, local "release-circuits" at the central station or exchange for effecting a release of any switch or switches employed thereat for establishing connection between a calling and a called subscriber's line, suitable "line-circuits", and means whereby the closure of a local circuit and the consequent release of a switch or switches is initiated by a subscriber over a "line-circuit".

60. The combination, in an automatic or subscriber-operated telephone system of the trunk-release type, of a plurality of switches, a switch-operating means common to all of said switches and normally connected with the latter, and automatic means adapted and operative to cause said switch-operating means to bring about a selective operation on the part of any and all idle switches upon the total mechanical disconnection of any switch from the said switch-operating means, local "release-circuits" at the central station or exchange for effecting a release of any switch or switches employed thereat for establishing connection between a calling and a called subscriber's line, suitable "line-circuits", and means whereby the closure of a local circuit and the consequent release of a switch or switches is initiated by a subscriber over a "line-circuit".

61. The combination, in an automatic or subscriber-operated telephone system of the trunk-release type, of an automatic "individual-switch" provided with a laterally and endwise movable plunger controllable by a certain subscriber for connective purposes only, but also controllable by other subscribers for selective purposes only, local "release-circuits" at the central station or exchange for effecting a release of any switch or switches employed thereat for establishing connection between a calling and a called subscriber's line, suitable "line-circuits", and means whereby the closure of a local circuit and the consequent release of a

switch or switches is initiated by a subscriber over a "line-circuit".

62. The combination, in an automatic or subscriber-operated telephone system of the

- 5 trunk-release type, of an automatic switching apparatus provided with a plurality of pivoted plungers, and means for operating the same for connective purposes, together with a rotatable member adapted to engage 10 all of said plungers and swing the same about their axes for selective purposes only, local "release-circuits" at the central station or exchange for effecting a release of any switch or switches employed thereat for 15 establishing connection between a calling and a called subscriber's line, suitable "line-circuits", and means whereby the closure of a local circuit and the consequent release of a switch or switches is initiated by a subscriber over a "line-circuit".

63. The combination, in an automatic or subscriber-operated telephone system of the trunk-release type, of a plurality of switches each capable of establishing any one of a 25 number of possible connections, manually-controlled means for causing any one of said switches to close a connection, and automatic means whereby each switch is released to perform a selective operation when its allotted subscriber hangs up his telephone, and whereby each switch is always ready and in position to close a preselected idle or non-busy connection, local "release-circuits" at the central station or exchange for effecting 30 a release of any switch or switches employed thereat for establishing connection between a calling and a called subscriber's line, suitable "line-circuits", and means whereby the closure of a local circuit and the 35 consequent release of a switch or switches is initiated by a subscriber over a "line-circuit".

64. A telephone system comprising an "individual-switch" provided with an electro-magnet, a support having openings for the cores of said electro-magnet, straps having their middle portions bowed away from each other, said straps having end portions adapted to engage said cores, line switching 45 mechanism operated by said magnet, and a clamping-screw extending through the middle portion of one strap and having a threaded engagement with the middle portion of the other strap, whereby a tightening 50 of said screw produces an endwise lengthening movement of said straps, and a consequent clamping of the said cores in place, and means for controlling said switch.

65. In a telephone system, the combination 60 of a plurality of trunk-lines, a subscriber's telephone line, a set of flexible spring-contacts for each trunk-line, a set of contacts for said telephone line, a stationary mounting for all of said contacts, means 65 for selecting a non-busy trunk-line, means

for pressing the contacts of the non-busy trunk-line against the contacts of the telephone line, and means for controlling the same over the telephone line.

66. In a telephone system, the combination 70 of a plurality of trunk-lines, a subscriber's telephone line, a set of flexible spring-contacts for each trunk-line, a set of stationary rigid contacts for said telephone line, a stationary mounting for all of 75 said contacts, means for selecting a non-busy trunk-line, means for pressing the contacts of the non-busy trunk-line against the contacts of the telephone line, and means for controlling the same over the telephone 80 line.

67. In a telephone system, the combination 85 of a plurality of trunk-lines, a subscriber's telephone line, a set of movable contacts for each trunk-line, a set of rigid contacts for said telephone line, a stationary mounting for all of said contacts, means for selecting a non-busy trunk-line, means for pressing the contacts of the non-busy trunk-line against the contacts of the telephone 90 line, and means for controlling the same over the telephone line.

68. In a telephone system, the combination 95 of a plurality of trunk-lines, a terminal for each trunk-line, a subscriber's telephone line, and automatic means for connecting the telephone line with a non-busy trunk-line, said means including a laterally and endwise movable member, means for moving said member sidewise to select a 100 non-busy trunk-line, means for causing said member to move endwise to engage the terminal of the non-busy trunk-line, and a talking circuit excluding said member.

69. In a telephone system, the combination 105 of a plurality of trunks, and a trunk-selecting switch mechanism, said mechanism provided with a swinging and endwise-movable member, means for swinging said member sidewise to select a non-busy trunk, 110 means for moving said member endwise to seize the non-busy trunk, and a talking circuit excluding said member.

70. In a telephone system, the combination 115 of a plurality of trunks, a calling line, a bank of flexible terminal contacts for the trunks, stationary terminal contacts for the line, and means for flexing the contacts of a non-busy trunk into engagement with the contacts of the calling line.

71. In a trunk-selecting switch mechanism, a plurality of flexible trunk-terminals, multiples of said terminals, a stationary terminal for each set of multiples, and means for flexing the trunk-terminals into contact 125 with the stationary terminal, and means for controlling said mechanism.

72. In a trunk-selecting switch mechanism, a laterally and endwise-movable member, trunk-terminal sockets adapted to be 130

entered by said member, and means for causing said member to select idle terminal sockets.

73. In a trunk-selecting switch mechanism, a calling line terminal, a stationary bank of flexible spring trunk-terminals, and means for moving said terminals into contact with a calling line terminal, and means for controlling said mechanism.

10 74. In a telephone exchange system, the combination of a line, a plurality of trunks provided with multiple terminal sockets, means by which one or more of said trunks are rendered busy, and a trunk-selecting switch mechanism for connecting the line with a non-busy trunk, said mechanism provided with a laterally and endwise-movable member adapted to enter any one of said trunk-terminal sockets.

20 75. In a telephone system, the combination of trunks, automatic means for selecting idle trunks ahead of the calls, swinging and endwise-movable plungers for seizing the preselected trunks, and talking circuits closed by and excluding said plungers.

25 76. In a telephone system, the combination of trunks for talking purposes, automatic means for selecting idle trunks ahead of the calls, and means including an endwise and laterally movable member automatically operated in advance of the calls to be in position for immediately engaging the preselected talking trunks in response to calling subscribers.

30 77. In a telephone system, the combination of trunks for talking purposes, automatic means for selecting idle trunks ahead of the calls, an endwise and laterally movable member for engaging and traveling from one trunk to another, and automatic means for moving said member from busy to idle trunks, whereby said member when idle is always at a preselected idle trunk.

35 78. In a telephone system, a plurality of trunks, a swinging member automatically operated to find an idle trunk by a step-by-step movement from one trunk to another, and automatic means for selecting another trunk when a subscriber seizes the said selected idle trunk, and a talking circuit excluding said member.

40 79. In a telephone system, the combination of a preselected idle talking trunk, a step-by-step operated member for engaging said trunk and preselecting the same, and means whereby said preselected idle talking trunk is seized by a calling subscriber, and a talking circuit excluding said member.

45 80. In a telephone system, the combination of trunks, automatic means for selecting idle trunks ahead of the calls, and subscribers' individual step-by-step operated traveling members for engaging and seizing the preselected idle trunks to extend talking circuit excluding said members.

81. In a telephone system, a plurality of trunks, a mechanism common to a plurality of subscribers for selecting idle trunks ahead of the calls, and a plurality of traveling members for traversing the trunks while not in use for talking purposes.

70 82. In a telephone system, a plurality of trunks for talking purposes, a traveling member for traversing said trunks while not in use for talking purposes, and means for so operating said member to find idle trunks ahead of the calls.

75 83. In a telephone system, a plurality of groups of automatic switches, automatic selectors having vertical motion to select groups and rotary motion to automatically select an idle switch in any selected group, traveling plungers each individual to a subscriber, means common to the subscribers for moving said plungers to select idle selectors ahead of the calls, means by which calling subscribers operate said plungers to seize the preselected idle selectors, and movable bank contacts operated by said plungers in the seizure of idle selectors.

80 84. In a telephone system, a plurality of groups of automatic switches, automatic selectors having vertical motion to select groups and rotary motion to automatically select an idle switch in any selected group, a traveling plunger, means for moving said plunger to select idle selectors ahead of the calls, means for operating said plunger in response to a call to seize the preselected idle selector, and movable bank contacts operated by said plunger in the seizure of idle selectors.

85 85. In a telephone system, automatic switches and means for preselecting an idle switch, and electromagnetically-actuated non-conducting plungers having lateral and endwise movement operated by calling subscribers to seize preselected idle automatic switches, said switches having vertical motion to select predetermined groups of lines and rotary motion to connect with a line in any selected group.

90 86. In a telephone system, the combination of means for establishing a connection between a calling and a called subscriber's line, said means including trunks, mechanism for automatically selecting idle trunks ahead of the calls, subscribers' individual electromagnets, plungers having lateral and endwise movement operated by said magnets for seizing the preselected idle trunks, and means for automatically opening the circuits of said magnets on the called lines.

95 87. In a telephone system, the combination of means for establishing a connection between a calling and a called subscriber's line, said means including a plurality of trunks, a plunger having lateral and endwise movement, a subscriber's plunger-controlling electromagnet responsive,

when the subscriber calls, to seize an idle trunk, and means for automatically opening the circuit of said magnet when the line thereof is called.

- 5 88. In a telephone system, a plurality of trunks, a calling line, a bank of terminal contacts for said trunks, stationary terminal contacts for the line, and means initiated after the receiver has been raised from 10 the hook for causing the contacts of a non-busy trunk to engage with the contacts of the calling line.

89. A telephone system comprising a subscriber's line, a subscriber's calling device 15 for sending the impulses necessary for calling any desired number, an "individual-switch" for said subscriber's line adapted and operative to respond to the first of said number-impulses, a trunk-line adapted to 20 be connected with the subscriber's line by the "individual-switch," and a switch connected with said trunk-line and adapted also to respond to the first of said number-impulses, whereby both switches are successively operated by the same momentary closing of a circuit.

90. A telephone system comprising a subscriber's line, a subscriber's switching means for producing the electrical impulses necessary for calling any desired number, an "individual-switch" for said subscriber's line, and another switch connected with said first mentioned switch, said "individual-switch" being adapted to respond to the first electrical impulse produced by the operation of said subscriber's switching means, so as to connect the two switches together before said impulse ceases, and said last mentioned switch being also adapted to respond 40 to said impulse and to perform an operation corresponding to the first digit of the called number.

91. A telephone system comprising a couple of automatic step-by-step switching machines, and a subscriber's calling device adapted for producing the electrical impulses necessary for operating the said switching machines in accordance with the called number, one of said machines being responsive to the first number-impulse and operative to establish a connection with the other machine upon the initial actuation of said calling device, and said other machine being operative to then perform an operation corresponding to the first digit of the called number.

92. In a telephone system, the combination of trunks for talking purposes, automatic means for selecting idle trunks ahead 60 of the calls, a swinging member for engaging and seizing the idle trunks, and automatic means for keeping said member in alignment with a preselected idle talking trunk while not in use for talking purposes.

65 93. An automatic telephone system com-

prising a plurality of subscribers' lines, a plurality of trunk-lines allotted to and common to said subscribers' lines, but less in number than the said subscribers' lines, together with an individual-switch for each 70 subscriber's line, and means common to all of said subscribers' lines for operating said switches, each switch being capable of establishing connection with any one of said trunk-lines, but always ready and in position to establish connection with an idle trunk-line while the subscriber's line is out of use.

94. A telephone system comprising a plurality of subscribers' lines, a switch for each 80 subscriber's line, a plurality of trunk-lines, each switch having a series of trunk-line-terminals each connected with one of said trunk-lines, and automatic means whereby the seizure of any trunk-line compels the 85 switches of all idle subscribers' lines immediately to select the next idle trunk-line.

95. A telephone system comprising a plurality of switches each provided with a series of trunk-line-terminals, trunk-lines each connected with a terminal in each switch, and means whereby the seizure of any trunk-line compels all idle switches immediately to select the next idle trunk-line.

96. An automatic telephone system comprising a plurality of subscribers' lines, an individual-switch for each subscriber's line, a plurality of trunk-lines less in number than the subscribers' lines and each connected with all of said switches, automatic means for enabling any switch when operated to cause any and all idle switches to select the next idle trunk-line, whereby each switch is, when out of use, always ready and in position to establish connection between 100 its allotted subscriber's line and an idle trunk-line.

97. An automatic telephone system comprising a plurality of subscribers' lines, an individual-switch for each subscriber's line, a plurality of trunk-lines less in number than the subscribers' lines and each connected with all of said switches, and electrically-operated automatic means for enabling each switch when put in use to cause any and all 110 idle switches to select the next idle trunk-line, whereby each switch is, when not in use, always ready and in position to establish connection with an idle trunk-line.

98. An automatic telephone system comprising a plurality of subscribers' lines, a plurality of trunk-lines less in number than the said subscribers' lines, an individual-switch for each subscriber's line, each trunk-line being connected with all of said 125 switches, the said switches being each provided with a traveling circuit-closing device capable of establishing connection between its allotted subscriber's line and any one of said trunk-lines, and the system also 130

- comprising automatic means whereby each circuit-closing device, when put in use, causes any and all idle circuit-closing devices to select an idle trunk-line, and whereby each circuit-closing device is, when not in use, always ready and in position to establish connection between its allotted subscriber's line and one of said trunk-lines.
99. An automatic telephone system comprising a plurality of switches, a switch-operating means common to all of said switches and adapted for bringing about selective operations on the part of the same, each switch including within itself suitable means for effecting a closure of any connection selected by the said switch-operating means, and automatic means whereby the seizure of any connection by any switch causes any and all idle switches to simultaneously select the next idle connection, said switches being connected together and thus each adapted for closing any one of a certain number of normally-open electrical connections.
100. An automatic telephone system comprising trunks, a plurality of trunking switches, a switch-operating means common to all of said switches and adapted for producing only trunk-selecting operations on the part of said switches, each switch comprising within itself suitable means for effecting a closure of connection with any trunk selected by the said switch-operating means.
101. An automatic telephone system comprising a subscriber's line, a plurality of trunk-lines to be used by said subscriber in calling other subscribers, means whereby the same trunk-lines may be used by other subscribers, automatic circuit-closing means capable of establishing connection between the said subscriber's line and any one of said trunk-lines, and controllable by the said subscriber, together with automatic means adapted and operative to produce a selective operation on the part of said circuit-closing means while the latter are idle and each time one of said trunk-lines is temporarily appropriated for use by some other subscriber.
102. A telephone system comprising a ratchet device, an electro-magnet for actuating said ratchet device continuously in one direction, a bank of contacts, a switch-arm adapted to swing forward and back upon said contacts, so as to always engage one of said contacts, and transmitting connections for converting the continuous rotation of said ratchet device into a forward and back movement on the part of said switch-arm.
103. A telephone system comprising an electro-magnetically-actuated ratchet device adapted for continuous rotation in one direction, a bank of contacts, and a member for engaging said contacts, and always in contact therewith, together with means for convert-
- ing the continuous rotary motion of said ratchet device into a reciprocating motion on the part of said member.
104. A telephone system comprising a calling subscriber's line, a subscriber's individual trunk-selecting mechanism, switching machinery adapted to be operated by vertical and rotary impulses, and a subscriber's calling device for transmitting the said vertical and rotary impulses, together with means whereby the first vertical impulse effects a locking of the individual switch mechanism in the selected or desired position.
105. A telephone system comprising subscribers' lines, an individual trunk-selecting mechanism for each line, a switch-operating mechanism common to all of said individual mechanisms, subscribers' calling devices for transmitting the electrical impulses representing the number of any called subscriber, and automatic means whereby the first impulse transmitted by any calling device effects the operation of said switch-operating machine.
106. In a system for automatically trunking telephone lines into connections with other lines, the combination of a group of telephone lines, a plurality of trunk-lines less in number than said telephone lines, trunk-connecting means individual to each telephone line, adapted to close connection between calling telephone lines and pre-selected trunk-lines, and automatic trunk-selecting means common to all of the telephone lines, comprising a ratchet or step-by-step mechanism actuated automatically whenever connection is made with a pre-selected trunk-line, adapted to select an idle trunk-line each time a pre-selected trunk-line is seized by a calling telephone line.
107. The combination of telephone lines, a plurality of trunks, individual trunking means for each telephone line, comprising means for connecting a calling telephone line with a pre-selected trunk, and a trunk-selecting mechanism common to all said individual means, comprising means for causing a mechanical trunk-selecting operation on the part of all idle individual means each time a pre-selected trunk is seized by a calling telephone line.
108. The combination of telephone lines, a plurality of trunks, an individual automatic trunking means for each telephone line, a common automatic trunk-selecting mechanism for producing a mechanical trunk-selecting operation in the individual means of all idle telephone lines each time a trunk is seized by a calling line, each individual means comprising means for connecting the telephone line thereof with the pre-selected trunk.
109. The combination of trunks, telephone

- lines, as many multiple terminals for each trunk as there are telephone lines, means individual to each telephone line for connecting with idle and pre-selected trunk terminals, a common mechanism for producing mechanical operations in the individual means of all idle telephone lines each time a pre-selected trunk is seized, to select a new trunk for the next call, said trunks less in number than said telephone lines.
110. The combination of telephone lines, subscriber-controlled or operated apparatus for automatically trunking and finally connecting in accordance with the digits of any called number, trunk-lines leading to said apparatus, a set or series of trunk-line terminals for each telephone line, means for connecting a calling telephone line with the terminal of a pre-selected trunk-line, and automatic means for selecting a new or idle trunk-line for the next call.
111. In a telephone system, a plurality of automatic progressively-movable switches for extending a connection to a called line, release equipment for said switches, a trunk release circuit separate from the talking conductors for controlling said release equipment, a test circuit for the called line, means for applying a busy potential to the said test circuit, means responsive to the said potential for controlling said trunk release circuit.
112. In a telephone system, a plurality of automatic progressively-movable switches for extending a connection to a called line, release equipment for said switches, a trunk release circuit separate from the talking conductors for controlling said release equipment, a test circuit for the called line, means for applying a busy potential to the said test circuit, and means responsive to the said potential for controlling said trunk release circuit for applying a busy potential to the said test circuit, and means responsive to the said potential for controlling said trunk release circuit for releasing the switches.
113. In a telephone exchange system, means including a plurality of automatic switches for extending a connection from a calling to a called subscriber's line, automatic means for releasing all of said switches included in said connection if the called line is busy, and means then effective to transmit a busy signal to the calling subscriber.
114. In a telephone system, the combination with a calling and a called subscriber's line, of a plurality of automatic switches for connecting said lines, means for releasing said switches if the connection is attempted when the called line is busy, and means individual to the calling line for transmitting a busy signal to the calling subscriber.
115. In a telephone system, subscribers' lines provided with individual line switches, means whereby a calling subscriber can extend his line to a called subscriber's line, said means including the individual switch of the calling line and a trunk line accessible to any calling line, means for releasing the individual switch of the calling line if the called line is busy to restore said trunk line to common use, and means for then transmitting a busy signal to the calling subscriber.

Signed by me at Chicago, Cook county, Illinois, this 21st day of April, 1905.

ALEXANDER E. KEITH.
